UNITED STATES PATENT OFFICE.

GEORGE W. MANN, OF WEBB CITY, MISSOURI, ASSIGNOR OF ONE-HALF TO JACOB GRIPKA, OF WENTWORTH, MISSOURI.

SELF-FEEDER.

Application filed July 9, 1925. Serial No. 42,514.

To all whom it may concern:

Be it known that I, GEORGE W. MANN, a citizen of the United States, residing at Webb City, in the county of Jasper and 5 State of Missouri, have invented a new and useful Self-Feeder, of which the following is a specification.

This invention aims to provide a novel means for feeding grain to a thresher, so 10 constructed and governed that it will operate independently of the speed of the threshing cylinder, the device being automatically governed, in operation, the material to be threshed being caused to move 15 evenly and fairly to the thresher.

It is within the province of the disclosure to improve generally and to enhance the the utility of devices of that type to which the invention appertains.

20 With the above and other objects in view which will appear as the description proceeds, the invention resides in the combination and arrangement of parts and in the details of construction hereinafter described 25 and claimed, it being understood that changes in the precise embodiment of the invention herein disclosed, may be made within the scope of what is claimed, without departing from the spirit of the invention.

30 In the accompanying drawings:—

Figure 1 shows, in side elevation, a device constructed in accordance with the invention; Figure 2 is a transverse section; Figure 35 3 is an elevation showing the opposite side of the device from that depicted in Figure 1; Figure 4 is a top plan.

In carrying out the invention, there is provided a support or chute 1, including side 40 plates 2. An inclined deck 3 is located between the side plates 2 and is pivotally mounted at its inner end, as shown at 4. The outer end of the deck 3 has slots 5 receiving fingers 6 on a shaft 7 mounted to 45 rock in the support 1, the shaft 7 having a crank 8 which is resilient enough so that it can be engaged with a keeper 9 on the support 1, the fingers 6 projecting upwardly above the deck 3, at the discharge end of 50 the deck, and serving to regulate the passage of the material to be threshed, along the deck or inclined feeding board 3.

The deck 3 is supported for vertical swinging movement on the cranks 10 of a 55 shaft 11 mounted to rock in the support 1.

The shaft 11 is supplied with an arm 12, united by a spring connection 14 with a lever fulcrumed on the support 1, the lever, marked by the numeral 15, having resiliency enough so that it can be engaged with a keeper 16 on the support 1. The shaft 11 has a curved cam 17 cooperating with a curved arm 18 on one end of a horizontal shaft 19, supported for rocking movement at 20 on the chute 1. A retractile spring 21 is connected to the arm 18 of the shaft 19, and to the support 1, the spring serving to keep the arm 18 yieldably in proper relation to the cam 17 on the shaft 11.

At its inner end, the shaft 19 has an arm 22, engaged with a clutch 23 which serves to connect a gear wheel 24 with a shaft 25, the shaft 25 being journaled on the support 1. The shaft 25 carries a pulley roller 26 engaged by a belt conveyor 27 which is 75 passed about a pulley roller 28 on an idle shaft 29 journaled in the support.

Near to the inner end of the belt conveyor 27 is located a chaff and litter roller 30, which is corrugated, the roller 30 being 80 mounted on a shaft 31 journaled in the side plates 2 of the support 1. There is a pulley 32 on the shaft 31, the pulley 32 being engaged by a belt 33, cooperating with a pulley 34 mounted on one end of the shaft 25.

A pinion 35 meshes with the gear wheel 24 and is carried by a shaft 36 journaled on the support 1, the shaft 36 being supplied, at one end, with a fly wheel 37, and carrying, 90 at its opposite end, a pulley 38 driven by a belt 39—although the shaft 36, it will be understood, may be driven in any desired way.

The shaft 36 has cranks 40, supporting the 95 inner ends of feeder bars 41 extended above the deck 3, the feeder bars having depending projections 42. The outer ends of the feeder bars 41 are pivotally supported on links 43 which are pivoted at their upper ends to a 100 cross piece 44 extended between the side plates 2 of the support or chute 1.

The shaft 36 is driven by the pulley 38 or its equivalent, and the cranks 40 impart longitudinal reciprocation and up and down 105 swinging movement to the feeder bars 41. From the shaft 36, rotation is imparted to the chaff and litter roller 30 by a train of elements including the pinion 35, the gear wheel 24, the shaft 25, the pulley 34, the 110

belt 33, the pulley 32, and the shaft 31. The belt conveyor 27 is operated by the pulley roller 26 which is carried by the shaft 25. In connection with the driving of the belt conveyor 27, it is to be observed that the movement of the belt conveyor is dependent upon the clutch 23 which connects the gear wheel 24 with the shaft 25.

In the ordinary operation of the machine, the material to be threshed is carried by the belt conveyor 27 and is deposited on the deck 3 after having been engaged by the chaff and litter roller 30. The reciprocating feeder bars 41 carry the material along the deck 3, off the outer end of the deck, the passage of the material being regulated by the fingers 6.

In the event that the material begins to pack, jam, or collect between the feeder bars 41 and the deck, the deck 3 swings downwardly on its pivotal mounting 4, thereby causing the cranks 10 on the shaft 11 to rock the shaft 11. When the shaft 11 is rocked, as aforesaid, the cam 17 on the shaft 11, cooperating with the arm 18 of the shaft 19, rocks the shaft 19, thereby causing the arm 22 of the shaft 19 to throw out the clutch 23, the pulley roller 26 no longer deriving rotation from the shaft 36, and the movement of the conveyor 27 being stopped; the advancement of the material, by the conveyor 27, being stopped accordingly. When the jam between the feeder bars 41 and the deck 3 has been eased off, the parts are restored to their original positions. During the movement of the deck 3, above described, the spring connection 14 of Figure 3 yields. It is possible, however, to adjust the tilt of the deck 3, at the hand of an operator, through the instrumentality of the lever 15, the connection 14, the arm 12, the shaft 11 and the cranks 10. The amount that the fingers 6 project above the deck 3 may be regulated by rocking the shaft 7 with the crank 8, the crank 8 being engaged with the keeper 9, and the keeper 16 exercising an obvious function in connection with the lever 15.

It is to be observed that the fingers 6 serve to regulate, govern and control the flow of the material to be threshed, and the machine, therefore, includes two means whereby the flow of material is regulated. The projections 42 adjust themselves readily to the material and operate in conjunction with the parts 6. The governing of the flow of the material at the fingers 6 is independent

of the governing of the flow which takes place in other parts of the machine.

Having thus described the invention, what is claimed is:—

1. In a device of the class described, a deck mounted for swinging movement, a feeding means operating above the deck, a conveyor discharging upon the deck, mechanism for operating the conveyor, a clutch interposed in said mechanism, and means for throwing out the clutch, the last-specified means being operated by the deck as the deck swings downwardly responsive to an undue accumulation of material between the feeding means and the deck. 70

2. In a device of the class described, a deck mounted for swinging movement, a feeding means operating above the deck, a conveyor discharging upon the deck, mechanism for operating the conveyor, a clutch interposed in said mechanism, means for throwing the clutch out, said means being operated by the deck as the deck swings downwardly responsive to an undue accumulation of material between the feeding means and the deck, the last-specified means comprising a part which engages the deck, and a device under the control of an operator for actuating said part, thereby to change the angle of the deck, said device embodying yieldable means permitting the deck to swing downwardly responsive to an undue accumulation of material between the feeding means and the deck. 80

3. In a device of the class described, a deck mounted for swinging movement, a feeding means operating above the deck, a conveyor discharging upon the deck, mechanism for operating the conveyor, a clutch interposed in said mechanism, and means for throwing the clutch out, as the deck swings downwardly responsive to an undue accumulation of material between the feeding means and the deck, the last-specified means embodying shafts supported for rotation, one shaft being supplied with a cam, and being supplied with a crank engaging the deck, the other shaft having an arm cooperating with the cam, said other shaft being operatively connected with the clutch. 90 100

In testimony that I claim the foregoing as my own, I have hereto affixed my signature.

GEORGE W. MANN.
